METAL DOOR

Friederich Wilhelm Kiekert, Heiligenhaus,
GermanyApplication August 6, 1932, Serial No. 627,734
In Germany April 4, 1932

17 Claims. (Cl. 189—46)

The invention relates to metal doors, in particular vehicle sliding doors which consists of two stamped metal plates to be connected together. Hitherto, heavy rolled bars have been used for connecting these plates together, the door halves being riveted thereto, the rivets being inserted in transverse holes of the rolled bars. The latter were thereby greatly weakened, so that in spite of the heavy and expensive construction, only a very slight strength of the doors resulted. It has also been already sought to connect together by folding over or flanging turned over flanges on the edges of the doors, but here also insufficient strength was obtained, while the costs of production were comparatively high. If the flanges are directly riveted together, there takes place after a short time, especially in vehicular operation, a loosening and even a tearing out of the rivets.

The object of the invention is a metal door in which the said defects are avoided. According to the invention, the plates provided with flanges of the door are so connected that the overlapping or also butt joined flanges are held by clamping between outer and inner strips or fillets. By these means, an extraordinarily strong attachment of the parts together is attained and, furthermore, great lightness of the doors, as heavy rolled bars are entirely dispensed with. The riveting is not visible from the outside, this having been hitherto an important disadvantage, as even countersunk rivets show. Furthermore, great cheapening and utilization of the material employed is attained by the window bars as also the stop bars at the bottom and top edges of the door, as also stiffening pieces in the hollow space of the door consist of strips which are cut from the metal plates cut when making the window openings in the door plates, and the length of which corresponds at least to the width of the door.

The improved door is also distinguished by elastic protecting edges consisting of rubber on the door and the door frame or, in the case of double doors, on the abutting edges. These are preferably fastened by the single or multiple part rubber strips and the like being held in the working position by clamping means extending over their whole length and coming into operation simultaneously on this, for example by being tightened or loosened by a single handle.

The improved door is shown on the drawings in a number of embodiments as examples.

Fig. 1 is an elevation of a door embodying the novel features in one form; Figs. 2 and 3 are fragmentary side views of two bars included in this form; Figs. 2^a and 3^a are cross-sections of the

bars shown in Figs. 2 and 3 respectively; Fig. 4 is a fragmentary sectional view of two plates forming part of the form of door shown in Fig. 1; Fig. 5 is a fragmentary horizontal section showing the parts of the door in a partly assembled condition; Fig. 6 is a similar view showing a complete door assembly; Fig. 7 is a horizontal section showing an example of a window set into said door; Fig. 8 is a fragmentary section showing an example of the means for embodying a handle in said door; Fig. 9 is a similar view illustrating a method of fastening the buffer on the door; Fig. 10 is a similar view showing another arrangement of buffer and associated elements; Fig. 11 is a fragmentary face view showing an example of the mounting of guide bars on the door; Fig. 12 is a similar view showing the construction of a corner of said door; Fig. 13 is a section on the line 13—13 of Fig. 12; Fig. 14 is a horizontal section on the line 14—14 of Fig. 12; Fig. 15 is a fragmentary face view showing a roller and its mounting in said door; Fig. 16 is a fragmentary section on the line 16—16 of Fig. 15; Figs. 17, 18 and 19 illustrate another embodiment of the novel features in plan, side and sectional views respectively, and Fig. 20 is a fragmentary horizontal section showing still another arrangement of the buffer and its mountings.

In the embodiment according to Figs. 1—16, the door consists of the two plates 1 and 2 of stamped metal plate, which are provided on the side edges with overlapping flanges 3, 4. Flanges 5, 6 are also provided on the window apertures made by cutting out metal plates, which flanges meet together in the centre in butt joint. The attachment of the parts 1, 2 on the flanges 3, 4 takes place by rivets 7, which are fixed in a longitudinal row as projection rivets on bars 8 and with these, according to Figs. 4 and 5, are inserted through the rivet holes 9, 10 of the flanges 3, 4 and holes 11 of a section bar 12 or a second bar 13, and riveted, Fig. 6.

In the same way, the projecting rivets 15, 16 fastened in two rows on a bar 14 are passed through holes 17, 18 of the flanges 5, 6 and angle bars 19, and riveted. These and also other necessary bars such as window fold bars, door closing edges, stiffening insets and the like, are cut from the metal parts obtained by cutting the window openings out of the door plates, the length thereof corresponding at least to the width of the door, and are connected by riveting thereto. The section bars 12 serve for fixing protecting edges or buffers 20 consisting of rubber or the like. The angular bends 21 on the bars 12

form alone a gauge for the parts 1 and 2 of the door to be clamped therein, which considerably facilitates the exactitude and rapidity of the assembling of the door halves. The window frame 22 is inserted in the angle bars 19. This window frame has, for example, an S-shaped section and on inserting is pushed with one longitudinal edge according to the position shown in broken lines in Fig. 7 over rivet heads 23 projecting further forward on the window aperture and then deflected into this, whereupon from the front edge of the door screws 24 with bolt-like extensions 25 are screwed in front of the cross bar of the window frame located on this side of the window aperture, which without anything else hold all the parts in the position of use without any means of fastening being visible, and all the abutting edges on the window aperture being covered in the manner of a frame. Instead of the S-shaped section, a different suitable profile may be used.

The fixing of the door handle 26 takes place according to Fig. 8 by conical members 27 being inserted in conical holes or recesses 28 of an intermediate part or section 29 and being fixed by screws 30 which engage from the outer edge of the door by means of a bolt-like conical part 31 in a transverse hole 32 of the piece 27. The slide guide bars 33 on the faces of the door are inserted by pins 34 in the manner of a bayonet joint in holes 35 covered by the bars 33, and after pushing in the longitudinal direction are fixed by a screw 36 inserted from the edge of the door and which bears with a projection 37 against overlapping inwardly directed lugs 38 of the bars 35. The upper and lower edges of the door are closed by U-shaped bars or channel members 39, 40 which also form a gauge for the parts 1 and 2 of the door to be clamped therein, and which are clamped round by the U-shaped bar cross pieces. There are provided as shown in particular by Figs. 12 to 14, at the upper corners of the door insets 41 which by means of a projection 42 and rivets 43, are fixed on the U bars 39, 40 and by a rivet 44 on the longitudinal side of the door. The door lock can be fixed in one or more recesses 45 of the part 41 or the carrier lugs 46 can also be fixed by screws 47, 48. The corners of the door are extraordinarily strengthened by the said insets together with the rivets and screws. By this method of fixing the locks on the door, the result is attained that the protecting edges 20 can be carried straight through up to the top edge of the door so that they run uninterruptedly up to the lower edge 49 of the door frame.

As shown by Figs. 15 and 16, the corner connection 50 can also be made as housing for runner rollers 51. Such a corner connection may be used both at the bottom and also at the top of the door. The rubber fillet or the like 20 is provided at the fixing side with a metallic holder 52. This is bent into a number of corrugations and the cross bars of the fillet 20 are held and clamped by the pocket-like parts 53 of the holders 52. To fasten the latter on the door section bar 12 as shown by Figs. 1 and 9, a bolt 54 or hook 55 may be used at the bottom and a screw or the like 56 at the top.

According to Figs. 17-19, the two U-shaped bars 57, 58, are riveted together and projections 59 of the parts 1 and 2 of the door pass through slots of the bar 57 on which they are bent over in the form of a clamp. This connection is to be used in particular for finishing the upper and

lower edges of the door. It can, however, also be used on the front and back edges of the door. If necessary, at such places which are less visible, separate parts of the door can be fixed by rivets or the like directed towards the faces of the door. In this embodiment, the protecting edge 60 is made of closed box shape and fits by the fixing part in the H-shaped section bar 61, the limbs of which also extend on both sides over the edges of the door. In this way, ugly abutment edges are avoided and in particular on metal plate doors an extraordinarily strong section is attained at the edge of the door. The bar 61 may, however, also be of U-shape, which if necessary also fits into a recess of the door. The fixing of the bar 61 takes place by means of a metal fillet 62 which, for example, is fitted at the bottom into a strong hook 63 and is fixed at the top by a screw or the like. It then bears under pressure against the bottom 64 of the protecting edge 60. After loosening the screw or the like, the unit formed by 60, 62 can easily be removed from the edge of the door.

According to Fig. 20, the rubber fillet or the like 65 is formed at the back into an enclosed hollow body or chamber 66 which is filled with compressed air, it being clamped behind projections 67 on the section bar 68 of the door.

I claim:

1. A metal door comprising two stamped metal plates located in spaced surface parallelism, inwardly projecting overlapping flanges at the outer edges of said plates provided with a plurality of registering holes and spanning the space between said plates to close the same, an outer member located in surface engagement with said flanges on the outside and provided with holes in registry with those of said flanges, an independent inner flat bar located in the closed space between said plates in surface engagement with said flanges on the inside, and a plurality of rivets fixed upon and carried by said inner bar previous to its incorporation in said door and extending from said inner bar outwardly through the holes of said flanges and outer member whereby said metal plates are secured together.

2. A metal door comprising two stamped metal plates located in spaced surface parallelism, and provided with window apertures, inwardly projecting overlapping flanges at the outer edges of said plates provided with a plurality of registering holes, flanges on said plates at said window opening projecting toward each other and provided with a plurality of holes said flanges spanning the space between said plates to close the same, outer members located in surface engagement with said flanges on the outside and provided with holes in registry with the holes of said flanges, independent inner flat bars located in the closed space between said plates in surface engagement with said flanges on the inside, and a plurality of rivets fixed upon and carried by each of said inner flat bars previous to their incorporation in said door, said rivets projecting from said independent inner bars outwardly through the holes of said flanges and outer members whereby said metal plates are secured together.

3. A metal door comprising two stamped metal plates located in spaced surface parallelism, inwardly directed flanges on said plates for spacing the same apart, a channelled outside member extending lengthwise of the outer vertical edge of said door in surface engagement with said flanges, fastening means extending through said flanges and channelled member whereby said plates and

said channelled member are secured together, and a resilient protecting member extending lengthwise of said outer vertical edge of the door and secured in said channelled member.

5 4. A metal door comprising two stamped metal plates located in spaced surface parallelism, inwardly directed flanges on said plates for spacing the same apart, a channelled outside member extending lengthwise of the outer vertical edge of 10 said door in surface engagement with said flanges, fastening means extending through said flanges and channelled member whereby said plates and said channelled member are secured together, a resilient protecting member extending lengthwise 15 of said outer vertical edge of the door, a recessed member near the lower end of said channelled member, a co-operating member on said resilient member adapted to fit into said recessed member for fixing said resilient member in place at its 20 lower end, and a removable screw for fixing said resilient member in place at its upper end.

5 5. A metal door comprising two stamped metal plates located in spaced surface parallelism, and provided with window apertures, inwardly directed flanges at the outer edges of said plates and at said window opening for spacing said plates apart, fastening means co-operating with said flanges for securing said plates together, a channelled window frame in said window opening, inwardly extending projections at one side of said window opening projecting into the channel of said window frame, and screws having heads accessible at an edge of the door and extending inwardly of said window opening into the channel of said window frame in opposed relation to said projections whereby said window frame is removably fixed in said window opening.

6. A metal door comprising two stamped metal plates located in spaced surface parallelism, 40 means for securing said plates together, an intermediate section located between said plates and provided with tapered recesses, a door handle, tapered members carried by said door handle and fitting into said tapered recesses for mounting 45 said handle on the door and screws extending from an edge of the door through said intermediate section and tapered members for fixing said handle in place.

7. A metal door comprising two stamped metal plates located in spaced surface parallelism, said plates being provided with slots of keyhole shape and with apertures, means for securing said plates together, slide guide bars located on opposite faces of said door, headed pins on said bars adapted to fit into said slots for mounting said slide guide bars on said door over said slots, inwardly directed lugs on said bars projecting through said apertures into overlapping engagement between said plates, and a screw extending from an edge of said door and co-operating with said lugs to fix said slide guide bars in place.

8. A metal door comprising two stamped metal plates located in spaced surface parallelism, means for securing said plates together, interior U-shaped bars located between said plates and having their flanges in surface engagement with the inner faces of said plates at the upper and lower edges thereof for closing the spaces thereat and for spacing said plates apart, external 65 U-shaped bars fitted exteriorly over said plates at said upper and lower edges and having their flanges in surface engagement with the outer faces of said plates, and means for securing said U-shaped bars in place.

9. A metal door comprising two stamped metal

plates located in spaced surface parallelism, means for securing said plates together, a channelled member extending along a vertical edge of said door, a recessed rubber buffer extending lengthwise of said vertical edge, and a metallic holder carried by and fitted into the recess of said buffer whereby the latter is secured in said channelled member.

10. A metal door comprising two stamped metal plates located in spaced surface parallelism, 10 means for securing said plates together, an H-shaped member extending along an edge of said door and having flanges projecting over the outer surfaces of said plates, and a resilient buffer extending lengthwise of said edge and fixed in said 15 H-shaped member.

11. A metal door comprising two stamped metal plates located in spaced surface parallelism, means for securing said plates together, a channelled member extending along an edge of said 20 door, a holder located in said channelled member and provided with outwardly open recesses, and a U-shaped resilient buffer extending into said open recesses and being secured in said channelled member by said holder.

25 12. A metal door comprising two stamped metal plates located in spaced surface parallelism, means for securing said plates together, a channelled member extending along an edge of said door, a holder located in said channelled member, 30 a resilient buffer held in said channelled member by said holder, a bolt extending transversely across said buffer near one end thereof, a recessed member carried by said door near one end of said edge for receiving said bolt to secure said 35 buffer in place at said one end thereof, and a screw whereby said buffer is fixed in place at the other end thereof.

13. A metal door comprising two stamped metal plates secured together in spaced surface 40 parallelism, co-operating channelled members fitted exteriorly over the edges of said plates and interiorly between said plates respectively to close the space therebetween and to space said plates apart, some of said members being provided with 45 openings, strengthening inserts fitted between the plates at the corners thereof and provided with recesses in registry with said openings, and fastening means located at the edges of said door and extending through said channelled members 50 for securing said inserts in place.

14. A metal door comprising two stamped metal plates secured together in spaced surface parallelism, channelled members fitted over the edges of said plates to close the space therebetween, 55 some of said members being provided with openings, strengthening inserts fitted between the plates at the corners thereof and provided with recesses in registry with said openings, fastening means located at the edges of said door and extending through said channelled members for securing said inserts in place and rollers journaled in the recesses of said inserts and projecting outwardly beyond an edge of the door.

60 15. A metal door comprising two stamped metal plates secured together in spaced surface parallelism, channelled members fitted over the edges of said plates to close the space therebetween and provided with slots, and projections on said plates and extending through said slots, said projections 70 being bent into surface engagement with said channelled members for securing the same in place.

16. A metal door comprising two stamped metal plates located in spaced surface parallelism,

means for securing said plates together, a channelled member extending along an edge of said door, and a resilient buffer extending into and lengthwise of said channelled member, said buffer being internally divided into two independent closed chambers one of which contains compressed air whereby said compressed air buffer, at said chamber, is expanded into frictional engagement with said channelled member and secured 10 therein.

17. A metal door comprising two stamped metal plates located in spaced surface parallelism, means for securing said plates together, a rubber buffer extending along an edge of said door and internally divided into two independent closed chambers one of which contains compressed air, and means embracing and co-operating with said compressed air chamber for fastening said buffer to said door. 5

FRIEDERICH WILHELM KIEKERT. 10
